JOHN S. SWEENEY, OF GALVESTON, TEXAS.

FLUSH TANK.

Application filed June 21, 1927. Serial No. 200,488.

This invention relates generally to an improvement in flush tanks, and more particularly to a siphonic outlet for the water in the tank and a means for starting the siphon through the use of natural forces and without the use of valves.

The principal object of the present invention is the provision of a starting means for the siphonic outlet of flush tanks constructed to utilize the pressure of a trapped volume of air as a means for raising the water level to start the siphon.

A further object of the invention is the provision in a starter of this type of a trapped body of water, serving initially as a seal for the trapped body of air and thereafter as a water supply responsive to the pressure induced on said trapped body of air to be forced above the normal water line in the tank to start the siphonic action.

A further object of the invention is to provide for such a construction and relation of the operating parts that the necessity for any valve control or valve structure is entirely obviated, hence no valves are employed in the construction, there are no parts to leak or get out of order, and the life of the apparatus is limited only by the life of the material of which it is constructed.

The invention is illustrated in the accompanying drawings in which:

Figure 1 is a sectional view, partly in elevation, of a flush tank with the invention arranged therein, the parts being shown in normal positions.

Figure 2 is a similar view with the plunger elevated.

Figure 3 is a section on line 3—3 of Figure 1.

Figure 4 is a sectional view, partly in elevation, of a flush tank showing a modified form of siphon starting means, the parts being shown in normal positions.

Figure 5 is a similar view showing the parts in operative positions.

Figure 6 is a section on line 6—6 of Figure 5.

The improved siphonic starter, with particular reference to Figures 1 to 3, is arranged in the flushing tank 1 which may be of any usual or preferred construction, and includes an outlet pipe 2 exteriorly provided with radiating ribs or fins 3 shouldered at 4 above their lower ends. The outlet pipe 2 extends below the lower edges of the fins 3

and is exteriorly threaded at 5 to receive a clamping nut 6 and to permit the connection with the outlet pipe of the usual flush pipe leading to the bowl. The outlet pipe is secured to the tank by passing the threaded end through an opening 7 in the tank, a flange 7' being below the lower edges of the fins 3, such flange 7' resting upon a sealing gasket 8. The nut 6 is then applied to the outlet pipe below the tank and tightened to secure the pipe in upright position in the tank and seal the opening 7 against leakage around the pipe.

A water reservoir is adapted to be arranged in particular relation to the outlet pipe. This water reservoir comprises an inner pipe section 9, hereinafter termed the stand pipe, and a spaced cylindrical wall 10 connected by a bottom wall 11 with the lower end of the stand pipe and defining what may be termed a reservoir space 12 between the wall 10 and the stand pipe. The stand pipe has an internal diameter accurately fitting the outer edges of the ribs 3, so that in operative position the lower edge of the stand pipe rests upon the shoulders 4 and is thus spaced a slight distance from the bottom of the tank 1.

The stand pipe 9 is open at the top and extends a slight distance above the upper open end of the outlet pipe 2, the upper end of the reservoir space being also open with the wall 10 of a height substantially equaling the normal line of water level in the tank when full, indicated at 13. The upper edge of the stand pipe is inturned at 9' to direct the initial flow of water over such edge and into the outlet pipe 2.

The operative member of the starter is adapted for vertical movement relative to and guided on the wall 10. This operative member, which may be hereinafter termed the plunger, comprises an annular wall 14 adapted to more or less loosely fit the exterior of the wall 10, the purpose being to provide an accurate guide for the movement of the plunger as there is no necessity that these parts shall fit so as to prevent the passage of any water or air between them. The wall 14 of the plunger, which is of the same height as the wall 10, is provided at its upper end with a cover section 15 extending at right angles to the wall 14 and secured at its inner annular edge to a sleeve section 16 closed at the upper end, as

at 17, and open at the lower end. The sleeve section 16 depends below the cover section 15 of the plunger and is of such diameter as to provide a space 18 between such sleeve 16 and the stand pipe 9, and is about one and one-half times the area of outlet pipe 2.

The bottom 11 of the reservoir is provided with a bracket 19 having upstanding ears 20 to support the lever for operating the plunger, as will later appear, this bracket having a foot 21 to rest upon the bottom of the tank 1. The stand pipe 9 is formed with an opening 22, preferably by deflecting the upper edge of a slot in such stand pipe wall, this opening being positioned somewhat below the normal water line 13 of the tank. The sleeve 16 immediately below its juncture with the cover section 15 is formed with a comparatively small opening 23, for a purpose which will later appear.

The ears 20 support an upright 24 on the upper end of which is pivotally supported a lever 25, the inner terminal of which is connected to ears 26 rising from the closed end 17 of the sleeve 16. The outer end of the lever extends over the upper edge of the tank 1 and is connected to the usual pull chain 27, or obviously may be connected to any desired type of operating means. The usual inlet valve 28 controlled by a float 29 serves to admit water into the tank from the supply pipe 30 and through the float control the water level in the tank in the usual manner.

In normal positions it will be apparent that water stands in the space 12 and between the stand pipe and outlet pipe to a height corresponding to the normal water line in the tank, such level of course being below the upper end of the outlet pipe 2 and the upper end of the stand pipe 9. As the cover section 15 of the plunger is at or below the water level, the space between the sleeve 16, wall 10 and cover section 15 is filled with water.

As the pull chain is drawn upon, the plunger is lifted, drawing a supply of air through the outlet pipe 2 over the upper edge of the stand pipe, downwardly through the space 18 and around the lower edge of the sleeve 16 and into the space below the cover section 15 between the sleeve 16 and wall 14. That is to say, as the plunger rises the water beyond the sleeve 16 and below the cover section 15 is drawn upwardly, withdrawing the water from the space 18 until the air can pass through the space 18 around the lower edge of the sleeve and above the water below the cover section 15 and between the wall 14 and the sleeve 16.

It will, of course, be appreciated that during this operation, that is, the upward movement of the plunger, the sleeve 16 is also moving upwardly, thereby continually reducing the height of the water column

above the lower edge of the sleeve 16 between such sleeve and the stand pipe 9. This fact, together with the lowering of the level in this space 18, permits air to readily pass around the lower edge of the sleeve 16 and enter the space in the plunger above the body of water and between the sleeve 16 and wall 14. Of course, some air will enter this space through the opening 23, but the larger proportion of air necessary for the operation of the device will enter around the lower edge of the sleeve 16.

As soon as air enters this space, the water again seeks its level, sealing the lower end of sleeve 16, providing an air filled space 31 above the water below the cover section 15. On release of the pull on the chain 27, the plunger starts to move downwardly and the weight of the plunger must be sufficient to force the water up through the space 18 to fill outlet pipe 2. If desired and as preferred, this movement of the plunger may be rendered more positive and certain through the use of a weight 32 in the form of an annular member fitted over the upper projecting end of the sleeve 16 and resting on the cover section 15. In the downward movement of the plunger the air trapped in the chamber 31 exerts a downward pressure upon the water in the reservoir 12, forcing the same upwardly in the space 18 and over the top of the stand pipe 9 and through the outlet pipe 2, starting the siphonic action, the flow of water being continued of course as the lower end of the stand pipe is open to the water in the tank. The flush continues until the level of the water in the tank reaches the lower end of the stand pipe.

Following the initial displacement of the water from the reservoir 12 to start the siphonic action as described, there will of course be no further water withdrawn from the reservoir as in the siphonic action the water is drawn from the tank upwardly between the outlet pipe 2 and the stand pipe 9. During this siphonic action there is a tendency of course to draw the air within the plunger out with the outgoing water and this action tends to draw the air from the chamber 31 through the opening 23. This material reduction in air pressure in this chamber tends to the creation of a partial vacuum with the effect of permitting a part of the water rising between the outlet pipe 2 and the stand pipe 9 to flow through the opening 22 in the stand pipe and refill the reservoir 12. The parts are thus arranged for succeeding operation.

The essential characteristic of the construction is the fact that when the plunger is down or in normal position there is no air on the surface of the water in the reservoir below the cover 15 and between the walls 14 and sleeve 16, and that no space is provided for air accumulation until the

plunger starts to move upwardly. Thus the absence of movable parts would permit the device in providing for the start of the construction to be of glass. Any and all siphonic action takes advantage of well known natural laws.

It is of course apparent that the pressure of the trapped air in the chamber 31 will of necessity start the siphonic action rather than find its way downward between the walls 10 and 14, for the distance which this air has to force the water up over the edge of the stand pipe is materially less than the distance through which the air must force itself through a body of water between the walls 10 and 14, and hence the amount of pressure that would be required to force air out into the water at the bottom end of this opening, as it would require about 6/29 of a pound pressure to the square inch to force the air out this way, whereas it only requires 2/29 of a pound to the square inch to force the water over the top of the stand pipe. Hence whatever water may be accumulated between the walls 10 and 14 and the pressure of water standing in the tank 25 acts as an effective seal against the escape of air in this direction.

The reservoir is sure to refill during the operation of discharging but should the lever be pulled while the tank is empty and thereby discharging the water in the reservoir, the reservoir will refill in a short interval, as the water in the tank, after it is full, will find its way up the stand pipe 9, out through the opening 22 and into the reservoir, gradually displacing the air therein through the opening 23, until the reservoir is again filled and the parts ready for operation.

It is to be particularly noted that the construction is entirely and wholly free of any valves. The plunger is the only movable part, and this does not require any especial non-leaking fit with any other part. There are no movable parts to get out of order. The construction takes advantage of the natural tendency of air to be drawn into a chamber in which through the operation there is a tendency to reduce the pressure to less than atmospheric, and the further natural tendency of air under pressure greater than atmospheric to displace a column or body of water on which it acts.

Of course the weight 32 is to be determined to insure a sufficient air pressure to raise the column of water to the height necessary to support the siphonic action. Whatever air may accumulate within the sleeve 16 above the upper end of the stand pipe acts merely, if indeed it has any effect, to assist in the flow of water when once started.

The material of the various parts will of course be constructed with a view to prevent their deterioration in the contemplated use. While metal, such for example as aluminum, has proven satisfactory, the entire

water continues to flow into the tank, the tank will not overflow, as the water will find its way out through the flushing channels and flow out the pipe 2 when it reaches a sufficient height.

Figures 4, 5 and 6 show a slightly modified form of starter in which the sleeve element 16, or the equivalent thereof, which in the form shown in Figures 1, 2 and 3 is carried by and movable with the plunger, is held in more or less fixed relation with the stand pipe and is not operated in the movement of the starter.

In this form of the construction it will be noted that the parts including the tank, the outlet pipe, the connection of the outlet pipe to the tank, the water reservoir and stand pipe section are substantially identical with that shown in the construction illustrated in Figures 1, 2 and 3 and such parts will be indicated in Figures 4, 5 and 6 by the same numerals by which they are indicated in Figures 1, 2 and 3.

In the modified construction shown in Figures 4, 5 and 6, a sleeve member 33 is substantially similar in shape to the sleeve member 16 of the plunger of the main form of the device. In this instance, however, the sleeve member 33, when applied to the stand pipe, remains as a more or less fixed member with relation thereto and does not move in the operation of the plunger. This sleeve member 33, closed at the top at 34, is provided with an interior circular section or collar 35 having an accurate sliding fit with the stand pipe 9 and connected to the sleeve member 33 by radial webs 36, so that when the sleeve member is positioned on the stand pipe, the inner surface of the sleeve member will be spaced from the stand pipe exactly as is the sleeve member 16 of the preferred form. The stand pipe 9 is provided with a stop 37 which forms a limit for the downward movement of the collar 35 to so position the sleeve 33 that its upper closed end 34 is spaced slightly from the upper end of the stand pipe 9.

The plunger proper of the modified form includes an annular wall 38 which has a guiding fit with the wall 10 of the water reservoir, an upper right angled cover section 39 which overlies the water reservoir, and an upstanding cylindrical section 40 which encircles and is slightly spaced from the exterior surface of the sleeve 33. The cylindrical section 40 of the plunger is closed at the top, as at 41, and this top 41 is provided with the ears 42 for the lever connections, being in this respect identical with the form shown in Figures 1, 2 and 3. The stand pipe 9 of the modified form is

formed with an opening 43 arranged at the normal water line and similar in disposition and function to the opening 22 of the preferred form. The sleeve 33 is provided with an opening 44 corresponding in function to the opening 23 in the sleeve 16 of the preferred form. In this connection it is to be noted that the opening 44 in the sleeve 33 is at the water line when the tank is filled to its normal level and hence this opening 44 is partially sealed by the water.

With the parts in normal positions and the tank filled with water to the normal water line, it is noted that there is water to the top of the reservoir 12; that is, there is no air space between the top of the water in the reservoir and the cover section 39 of the plunger. As the top 41 of the plunger rests upon the top 34 of the sleeve 33, there is also a comparatively small air space between the exterior of the sleeve 33 and the cylindrical upstanding portion 40 of the plunger.

As the pull chain is drawn upon the plunger is elevated. This draws the air through the outlet pipe, around beneath the lower edge of the sleeve 33 and into the space now provided between the cover section 39 of the plunger and that between the top 34 of the sleeve 33 and the top 41 of the circular portion of the plunger. The plunger is provided with a weight 45 sufficient to operate the plunger, such weight being preferably in the form of a sleeve encircling the extension of the plunger and resting upon the cover section 39 as shown.

With the plunger raised, there is a considerable body of air trapped above the surface of the water between such water surface and the plunger closing section 39 and between the tops 34 and 41 of the sleeve and plunger, respectively. As the plunger descends this body of water is put under pressure commensurate with the weight used and the pressure acts upon the surface of the water to force the water upwardly between the sleeve 33 and the stand pipe 9 and over the upper edge of the latter into the outlet pipe, filling the latter for the starting of the siphonic action. As the plunger descends the air is permitted to escape through the opening 44, being drawn out therethrough by the siphonic action of the water. This tends to create a partial vacuum or at least a reduction of pressure within the reservoir above the then lowered water level, which reduction in pressure draws into the un-filled space in the reservoir a sufficient quantity of water to fill such space during the siphonic flow described, this refill taking place through the opening 43.

It is to be expressly understood that while the opening 43 in the stand pipe is serviceable for refilling the reservoir, it is not absolutely essential for, as previously stated,

the fit between the reservoir and plunger is not of a character to exclude the passage of water therebetween and it is at once apparent that under the pull of the reservoir incident to the lowered air pressure described, the water for the refill of the reservoir will find its way between the reservoir and plunger and over the upper edge of the reservoir in sufficient quantity for the refilling operation. Therefore, the openings 22 in the preferred form and 43 in the modified form are in nowise essential to a proper operation of the construction.

It will be understood that if desired the level of the cover section, 15 in the preferred form and 39 in the modified form, may be arranged somewhat below the normal level of the water in the tank. Then the partial vacuum formed in the upper portion of the reservoir during the siphonic action would result in a certain and sure refilling of the reservoir even without the use of the stand pipe opening (22 or 43), and even if the starter was operated while the tank was empty or partially filled. Of course the fit of the cover section (15 and 39) of the plunger on the upper edge of the reservoir wall must be such as to allow water to enter the reservoir when the plunger is down.

What I claim to be new is:

1. A flush tank adapted for siphonic discharge, including an outlet pipe, a water reservoir encircling the pipe, and manually operative means for producing a column of air above the water in the reservoir and exerting a pressure upon said column of air to utilize the water in the reservoir as a means for starting the siphonic action through the outlet pipe, the siphonic flow of water from the tank to the outlet pipe continuing without withdrawing the water in the reservoir.

2. In a flush tank, an outlet pipe therefor, a reservoir surrounding the outlet pipe and sealed thereagainst except at the extreme upper end, and a plunger operative relative to the reservoir to initially trap a body of air above the water in the reservoir in the initial movement of the plunger and utilize this body of air as a pressure medium to displace the water of the reservoir to start the siphonic action through the outlet pipe, the siphonic flow of water from the tank to the outlet pipe continuing without withdrawing the water in the reservoir.

3. In a flush tank, an outlet pipe, a reservoir having an inner wall surrounding and spaced from the outlet pipe, the space between said inner wall and outlet pipe being open to the tank at the bottom, and means operative with respect to the reservoir to initially provide a trapped body of air overlying the water in the reservoir and thereafter exert sufficient pressure on said body of air to raise the water in the reservoir.

above the top of the outlet pipe to start the siphonic action, the flow of water from the flush tank to the outlet pipe under the siphonic action being directly between the

outlet pipe and the inner wall of the reservoir to deplete the tank without withdrawing the water in the reservoir.

4. In a flush tank, an outlet pipe, a reservoir surrounding the same, the inner wall of the reservoir forming a stand pipe extended above the outlet pipe, and a plunger having a sleeve extending into the reservoir between the walls thereof and a top sealing the space in the reservoir between such sleeve and outer wall of the reservoir.

5. In a flush tank having an outlet pipe, a stand pipe surrounding and spaced from the outlet pipe, the bottom of the stand pipe being open to the water in the tank, a reservoir 20 surrounding the stand pipe, said reservoir being closed at the bottom and terminating at the upper end substantially at the normal water line of the tank, and a plunger slidably encircling the reservoir and having 25 a sleeve section depending into the reservoir inwardly of the outer wall thereof.

6. In a flush tank having an outlet pipe, a stand pipe surrounding and spaced from the outlet pipe, the bottom of the stand pipe being open to the water in the tank, a reservoir surrounding the stand pipe, said reservoir being closed at the bottom and terminating at the upper end substantially at the normal water line of the tank, a plunger 30 slidably encircling the reservoir and having a sleeve section depending into the reservoir inwardly of the outer wall thereof, said plunger including an upper portion forming an extension of the sleeve and closed 35 beyond the upper end of the stand pipe. 40

7. In a flush tank having an outlet pipe, a stand pipe surrounding and spaced from the outlet pipe, the bottom of the stand pipe being open to the water in the tank, a reservoir surrounding the stand pipe, said reservoir being closed at the bottom and terminating at the upper end substantially at the normal water line of the tank, and a plunger slidably encircling the reservoir and having

a sleeve section depending into the reservoir inwardly of the outer wall thereof, the stand pipe being formed with an opening below the upper end of the reservoir. 50

8. In a flush tank having an outlet pipe, a stand pipe surrounding and spaced from the outlet pipe, the bottom of the stand pipe being open to the water in the tank, a reservoir surrounding the stand pipe, said reservoir being closed at the bottom and terminating at the upper end substantially at the normal water line of the tank, and a plunger slidably encircling the reservoir and having a sleeve section depending into the reservoir inwardly of the outer wall thereof, the sleeve being formed with an opening in line with the top edge of the reservoir. 55 60 65

9. In a flush tank, an outlet pipe, means for confining a body of water surrounding the outlet pipe, the surface of said body of water being below the upper edge of the outlet pipe and having an unrestricted path of communication with said outlet pipe, and means whereby a trapped body of air is initially positioned above said confined body of water and thereafter utilized to exert pressure upon said confined body of water to force a portion of the same along said unrestricted path to fill the outlet pipe to start siphonic action. 75

10. In a flush tank, an outlet pipe, means 80
for confining a body of water surrounding
the outlet pipe, the surface of said body of
water being below the upper edge of the
outlet pipe and having an unrestricted path
of communication with said outlet pipe, and 85
means whereby a trapped body of air is
initially positioned above said confined
body of water and thereafter utilized to
exert pressure upon said confined body of
water to force a portion of the same along 90
said unrestricted path to fill the outlet pipe
to start siphonic action, said trapped body
of air being withdrawn during the siphonic
movement of the water to provide for re-
plenishing said confined body of water. 95

In testimony whereof I affix my signature.

JOHN S. SWEENEY,
